(57) **CLAIM**

We claim the ornamental design for a photo cover for portable electronic device, as shown and described.

DESCRIPTION

FIG. 1 is an exploded rear perspective view of a photo cover for portable electronic device, showing our design with components separated for clarity of disclosure;

FIG. 2 is a rear perspective view thereof with components shown in an assembled state;

FIG. 3 is a rear elevational view thereof;

FIG. 4 is a front elevational view thereof;

FIG. 5 is a right-side elevational view thereof;

FIG. 6 is a left-side elevational view thereof;

FIG. 7 is a top plan view thereof;

FIG. 8 is a bottom plan view thereof;

FIG. 9 is a cross-sectional view thereof, taken along line 9-9 of FIG. 3; and,

FIG. 10 is a cross-sectional view thereof, taken along line 10-10 of FIG. 3.

The broken lines immediately adjacent shaded surfaces represent boundaries of the claimed design. All other broken lines depict unclaimed environment. All broken lines form no part of the claimed design.
